UNITED STATES PATENT OFFICE.

CHARLES E. DILLINGER, OF SANTA MARIA, CALIFORNIA.

GAME BALL.

Application filed June 15, 1923. Serial No. 645,653.

To all whom it may concern:

Be it known that I, CHARLES E. DILLINGER, a citizen of the United States, residing at Santa Maria, in the county of 5 Santa Barbara and State of California, have invented certain new and useful Improvements in Game Balls, of which the following is a specification.

This invention relates to improvements in 10 inflatable game balls, such for example as basket balls, foot balls, volley balls, and the like. In the ordinary game ball the leather casing is provided with a slit or mouth through which the bladder is introduced and 15 removed and which is closed by one or more lacing strings. However, in view of the rough usage to which such balls are subjected, the lacing strings soon become worn and break, and furthermore a laced mouth 20 presents a more or less uneven surface which is undesirable, it being necessary, in such articles, to have the exterior of the casing as smooth and as free from projections or recesses, as is possible. It is therefore one 25 of the important objects of the invention to provide, in a game ball, a novel means for closing the mouth of the casing which means will effectually maintain the mouth closed and the presence of which will at the same 30 time be practically unnoticeable. In other words, the invention contemplates the provision, in the casing of an inflatable game ball, of a mouth and closing means therefor so constructed that the surface contour of 35 the ball will not be altered to any appreciable extent by the presence of said mouth and its closing means.

Another important object of the invention is to so construct the closing means for the 40 mouth of the ball casing that the mouth may be opened or closed practically instantly and without any difficulty whatsoever being experienced, this construction obviously presenting marked advantages over a mouth 45 which requires to be laced.

Another object of the invention is to provide a novel arrangement of the inflating valve for the bladder, the construction being such that the presence of the valve will 50 not be noticeable because of any projecting parts, and will at the same time be readily accessible when it is desired to inflate or deflate the ball.

In the accompanying drawings:

Figure 1 is a perspective view of a basket

ball constructed in accordance with the present invention;

Figure 2 is a transverse sectional view taken substantially on the line 2—2 of Figure 1 looking in the direction indicated by 60 the arrows;

Figure 3 is a diametric sectional view taken in a plane substantially at right angles to the plane of Figure 2;

Figure 4 is a fragmentary perspective 65 view illustrating the two sides of the mouth of the casing relatively separated, and illustrating also the key which locks the sides of the mouth in closed relation.

In the drawings, the casing of the ball is 70 indicated in general by the numeral 1 and the inflatable bladder by the numeral 2. The casing 1 of the ball is made of leather or hide as usual, and the bladder 2 is preferably 75 of rubber, these two main parts of the ball being, when inflated, spherical, ellipsoidal, or of any other required contour. The casing 1, likewise, may be made up of any desired number of sections, and the sections 80 may be shaped and united in any of the usual ways. However, in order that the inflatable bladder may be inserted into the casing and removed therefrom, as occasion may require, the casing is, as is customary, 85 provided with a mouth indicated by the numeral 3. This mouth may be formed by omitting the stitching for a suitable distance in the length of one of the seams uniting the segments of the casing, or it may be provided by forming an incision or slit directly 90 in one of the segments. The former procedure is, however, preferable, and the segments, which are in this instance specifically indicated by the numeral 4, have extended 95 marginal portions at their meeting edges, which marginal portions are cut away or recessed at equally spaced intervals as at 5 thereby providing between the notches or recesses tongue portions 6. These tongue portions are wrapped about short tubular 100 sleeves 7 and are stitched to the bodies of the respective segments at the inner side thereof. The tubular sleeves 7 are of a length corresponding to the width of the respective tongue portions 6 by which they are enclosed so that the ends of the sleeves 105 are flush with the lateral margins of said tongue portions. In this manner, a series of spaced eyes are provided along each side of the mouth of the casing, and the eyes at 110

the two sides are preferably relatively staggered so that they will interfit or interdigitate when the mouth of the casing is closed, it being understood that the eyes are of a 5 width equal to the width of the recesses 5 in which they are received, so that the eyes will abut end to end throughout the two series and form a continuous tube which is 10 designed to receive the locking key as will presently be explained. The eyes are preferably so formed and arranged that their outwardly presented sides will be substantially flush with the outer surface of the casing of the ball and therefore the spherical or ellipsoidal contour of the ball is 15 maintained and there are no projecting parts which would be liable to interfere with skillful use of the ball.

The locking key above referred to is indicated in general by the numeral 8 and the said key comprises a suitable length of wire or small rod material indicated by the numeral 9 which is provided at one end with a head or finger piece 10 which may be 20 formed in any suitable manner as for example by bending this end of the wire upon itself. Eyelets 11 are provided one at one end of the series of eye members 6 at one side of the mouth 3, and another at the opposite end of the other series of eyes at the other side of the said mouth. Each of these eyelets is preferably formed from a length of wire bent to provide an eye 12 and shank portions 13 which portions are disposed to straddle the edges of the casing segments which define the mouth of the casing, the extremities of the shank portions being caused to pierce the segments and being overturned or riveted. The eyelets 25 11 are spaced from the next adjacent eyes 6 of the respective series a distance equal to the space between the said eyes 6 so that when the eyes 6 are interfitted or interdigitated as previously described, the eyelets 11 will be located at opposite ends of the two 30 matching series of eyes 6. With the parts thus assembled the key 8 is inserted through the eyes and eyelets thus connecting them together in alinement and effectually closing 35 the mouth of the casing. The wire shank 9 of the locking key is preferably curved on an arc corresponding to the curvature of the surface of the ball when inflated, as clearly illustrated in Figure 3 of the drawing.

From the foregoing it will be evident that so far as the feature of the casing mouth is concerned, the invention provides means whereby the mouth may be quickly 40 and conveniently closed and securely locked, the means being equally as readily manipulated to permit of opening of the mouth for the removal or introduction of the inflatable bladder. The closing means for the mouth is furthermore of such a nature that 45

it is devoid of any parts or portions projecting beyond the normal surface of the ball, and in fact the presence of the mouth and its closing means will not be particularly noticeable when the mouth is closed. 50

Another feature of the invention resides in the novel manner in which the inflating valve for the bladder 2 is mounted. The valve is indicated in general by the numeral 14 and the same comprises a tubular casing 55 15 in which is housed a spring seated check valve 16 which may be of the well known type employed in pneumatic tire valves. The numeral 17 indicates a collar which is interiorly threaded as indicated by the numeral 18 and to which is secured a circular attaching base 19 of rubber which in turn is secured to the inner side of the outer casing, the threaded opening of the collar 17 being presented concentric to an opening 20 60 formed in the wall of the said casing 1. The valve casing 15 is exteriorly threaded as indicated by the numeral 21 and is removably threaded into the said collar 17 as clearly shown in Figure 3 of the drawings. 65 The casing 15 of the valve extends through an opening formed in the bladder 2, and an attaching and sealing disc 22 of rubber is applied to or formed upon the bladder 2 at the point of passage of the valve casing 70 therethrough and is united to the said casing. It will be evident at this point that the valve casing may be threaded into the collar 17 so as to anchor the bladder 2 to the casing 1, the parts being, however, separable upon deflation of the bladder and rotation of the same together with the valve casing 15 to unthread the casing from the 75 said collar. A small screw cap 23 is removably threaded into the outer end of the 80 valve casing and is preferably provided with a transverse groove 24 to receive the bit of a screw driver whereby it may be readily removed for the purpose of attachment of a pump tube to the valve casing to 85 inflate the bladder, and may be replaced to 90 close the valve casing after the bladder has 95 been inflated.

A protective flap 25 is secured to the inner side of the casing of the ball at one 100 side of the mouth therein and is adapted to extend across the said mouth and to lie between the bladder and the closure for the mouth. This flap, of course, serves to prevent mutilation of the bladder by the closure 105 means.

Having thus described the invention, what is claimed as new is:

1. In an inflatable game ball, a casing 115 having a mouth provided at its opposite sides with a series of recesses defining cylindrical tongue portions which are united to the inner side of the wall of the casing to provide loops, bearing sleeves housed within the loops and covered thereby, the loops 120 125 130

and bearing sleeves at the opposite sides of the mouth being arranged in staggered relation whereby the bores of the sleeves will assume an alined relation when the mouth is closed, and a cylindrical locking rod removably fitted through the several bearing sleeves and maintaining the mouth closed.

2. In an inflatable game ball, a casing having a mouth provided at its opposite sides with a series of recesses defining tongue portions which are united to the inner side of the wall of the casing to provide loops, bearing sleeves housed within the loops and covered thereby, the loops and bearing sleeves at the opposite sides of the mouth being arranged in staggered relation whereby the bores of the sleeves will assume an alined relation when the mouth is closed; an eyelet at each side of the mouth and ar-

ranged near the adjacent loops, and a locking member fitting through the bearing sleeves and the adjacent eyelets.

3. In an inflatable game ball, a casing having a mouth provided at its opposite sides with eyes positioned to assume an alined relation when the mouth is closed, eyelets disposed at the opposite ends of the mouth and each formed of a single length of wire having one end thereof secured to the casing and its other end extended over the edge of the casing at the mouth to produce an eyelet, and a locking member extending through said eyes and engaging the eyelets.

In testimony whereof I affix my signature.

CHARLES E. DILLINGER. [L. s.]
